UNITED STATES PATENT OFFICE.

GEORGE MAAG, OF AKRON, OHIO, ASSIGNOR TO THE XXTH CENTURY HEATING AND VENTILATING COMPANY, OF AKRON, OHIO.

GRATE.

SPECIFICATION forming part of Letters Patent No. 707,855, dated August 26, 1902.

Application filed February 7, 1902. Serial No. 92,997. (No model.)

To all whom it may concern:

Be it known that I, GEORGE MAAG, a citizen of the United States, residing at Akron, in the county of Summit and State of Ohio, have invented a certain new and useful Improvement in Grates, of which the following is a specification.

My invention has relation to grates for furnaces, stoves, &c.; and the objects of my invention are to produce a grate which can readily and easily be cleared from accumulated ashes and the like and one in which all parts are readily accessible; and a further object is to make the front portion of the grate capable of being lowered when desired and finally to pivot the grate so that its entire surface is easily capable of being rotated.

To attain the aforesaid objects, my invention consists in the peculiar and novel construction, combination, and arrangement of parts hereinafter described and then specifically claimed, reference being had to the accompanying drawings, forming a part of this specification, and in which drawings similar reference-numerals indicate like parts in the different figures.

In the accompanying drawings, Figure 1 is a plan of my improved grate with the ash-pit surrounding it; Fig. 2, an inverted plan of the grate and ash-pit. Fig. 3 is a section at the line *xx* of Figs. 1 and 2, and Fig. 4 a front elevation looking from the bottom of Fig. 1.

In the drawings, 1 is an ash-pit for furnaces or stoves having sloping sides and having at the level of the upper surface of the grate to be described a flange on which the fire-pot is placed. Extending from the inside of the ash-pit below the grate-level is an arm 2. This arm is either made in a separate piece and bolted or screwed to the inside face of the ash-pit or else is made integral therewith, the former construction being preferable. The inner end of this arm 2 terminates in a cylindrical head perforated vertically to form a journal-bearing 3. For the sake of strengthening the arm 2 there are two arms 13, extending from the journal-bearing head 50 to the inner walls of the ash-pit and there fastened.

The grate portion proper consists of two parts 4 and 5, so constructed that when placed together they form substantially a round grate with projecting lugs on their entire outer periphery. The portion 4 of this grate has depending from its under surface a pin 6, arranged to enter the bearing 3, on which it is free to swing horizontally. This pin 6 is placed squarely in the center of the entire 60 grate, and the extended or free end of the portion 4 is designed to swing with the pin 6 as a pivot. On the upper face of the arm 2 and integral therewith is an arm 14, made in the arc of a circle with the pin 6 as a center. 65 This arm is designed to support the swinging end of the portion 4 as it rotates. Extending from the under face of the portion 4 laterally are two trunnions 7, properly mounted and integral with the main body portion 4. The 70 other portion 5 of the grate is arranged to inclose more or less closely all sides of the portion 4 excepting its rounded outer edge. The portion 5, hereinafter designated as the "dumping-grate," has on either side of the opening 75 therein, which enables it to surround the portion 4, two lugs 8, in which are deep notches to inclose the trunnions 7 of the portion 4, thereby supporting the dumping-grate by a pivot-joint with the portion 4. These trunnions 7 80 and lugs 8 form such a union between the two portions of the grate as will cause them to rotate horizontally together with the pin 6 as an axis by means of a projecting arm 9, passing through the doorway of the ash-pit. On 85 either side of the doorway of this ash-pit are journals 10 in alinement with each other and generally integral with the body of the ash-pit, and between these journals is swung a bail 11. This bail 11 is used to support the 90 extended arm 9, and when the bail is in the position in the figures the entire upper surface of the grate will be in one plane. The dumping portion 5 of the grate is lowered into the position shown by dotted lines in 95 Fig. 3 by giving a semirotation to the bail 11, which permits the arm 9 and the dumping portion 5 to be lowered or inclined toward the doorway of the ash-pit, but retains it there from complete descent to the ground-line. This bail 11 is arranged when swung 100 upward into the position shown in the fig-

ures to be prevented from falling forward by encountering a stop 12 on one of the journals 10, and this stop is so placed that the bail when in an upright position will slightly 5 overhang and rest against it. For ordinary shaking the arm 9 is rocked horizontally, causing the entire grate to move together, and this is done while the bail 11 is raised. When it is desired to remove large clinkers, 10 the bail 11 is lowered with the arm 9, permitting ready access through the doorway of the ash-pit to substantially all parts of the surface of the grate, and the portion 4 of the grate remains horizontal during this operation. 15 In rotating or shaking the grate horizontally the portion 4 swings with the pin 6 as its center, and its outer end is supported by the concentric arm 14 and is thus prevented from being broken by the weight resting upon it. In removing the grate for 20 repairs or other reasons the dumping portion 5 is easily raised from engagement with the trunnions 7, which permits the portion 4 to be lifted from its pivot.

25 Having thus described my invention, what

I claim, and desire to secure by Letters Patent, is—

1. The combination in a grate for furnaces and stoves, consisting of a two-part grate pivotally hinged together, a pivot for the entire grate mounted on one of said portions, an arm mounted on the other portion and means as a swinging bail to vary the inclination of one of said portions. 30

2. The combination in a grate for furnaces and stoves of a two-part grate a lever mounted on one of said parts a swinging bail mounted in said ash-pit arranged when swung in one position to keep said grate level, and when swung in the other direction to lower 40 one of the portions of said grate into an inclined position.

In testimony that I claim the above I hereunto set my hand in the presence of two subscribing witnesses.

GEORGE MAAG.

In presence of—

C. E. HUMPHREY,
C. P. HUMPHREY.
